UNITED STATES PATENT OFFICE.

JAMES A. HORTON, OF WORCESTER, MASSACHUSETTS.

CONTINUOUS WIRE-DRAWING MACHINE.

Application filed October 25, 1921. Serial No. 510,291.

To all whom it may concern:

Be it known that I, JAMES A. HORTON, a citizen of the United States, residing at Worcester, in the county of Worcester and State of Massachusetts, have invented new and useful Improvements in Continuous Wire-Drawing Machines, of which the following is a specification.

This invention relates to wire drawing machines of the continuous type. In the operation of such machines wire is drawn down in a continuous operation by a series of passes through wire drawing dies of successively smaller diameter, being drawn through the dies by drums about which the wire is wrapped. The course of the wire is, in principle, thus:—It passes through the first die, then around the first drawing drum in as many wraps as is necessary to apply the required drawing pull, then through the second die and around the second drawing drum, and so on through as many dies and around as many drums as the machine may be provided with, until finally it passes through the last die and is wound up on the final drum, which usually is also a receiver for a substantial length of wire, and is called the "finishing" drum. Before being drawn the wire, or rod to be made into wire, is first coated with a suitable lubricating material, in order to permit it to pass smoothly and evenly through the die without sticking. This coating, unless it be rubbed off by some other cause than contact of the wire with the dies, remains on the wire throughout the entire course of the drawing operation, being elongated with the wire but preserving its continuity and enabling the wire to be drawn through the entire series of dies and to be reduced in diameter in the required degree, without need of renewal. But if the coating be removed at any stage, it causes the wire to stick in the following die or dies and to be roughened or perhaps broken; at any rate it prevents the wire being drawn uniformly to the required gauge and with true cross section.

In the operation of continuous wire drawing machines as heretofore made, there has been some slip of the wire on one or more of the drums. It has not been found possible to design positive driving gearing which will drive all of the drums at their respectively correct speeds to take up the wire as

fast as it is delivered by the preceding drum plus the elongation of the wire in passing through the preceding die. The main reason for this fact is that unavoidable wear on the dies in the course of the drawing operation enlarges the holes which determine the gauge of the wire and therefore diminish its elongation, so that even if the driving mechanism is properly proportioned when the dies are all of the exactly correct size, the speed of the drums becomes too rapid after some wear of the dies has occurred. Other conditions, such as varying hardness and ductility of the wire may cause variations in the rate at which the wire passes to a certain drum of the series, and if the wire is not taken up fast enough by that drum, then enough tension will not be maintained on the next preceding drum and slipping of the wire on the latter drum will occur. And also if the following drum is driven at a speed to take up the wire faster than the rate of delivery from the preceding drum, plus the elongation at the die, then the wire will be broken.

Consequently it has been the custom of makers of continuous wire drawing machines to provide for slipping of the wire on all of the drums except the final or finishing drum. Slipping on that drum is impossible because the finished wire is accumulated on it. This effect is usually accomplished by making the speed of the finishing drum a certain amount less than the speed which appears by calculation as correct when the dies are of the correct size and the wire of uniform ductility. The reduction from such calculated speed is enough to take care of all accumulated variations in the elongation of the wire, but as it is less than enough to take the entire elongation of the wire plus the rate of delivery due to the speed of the preceding drums, the tension of the wire wrapped around the preceding drums is relaxed and one or more of such drums necessarily slips. The slipping of the drums chafes the wire and removes the coating at that side of the wire which rubs against the drum, with the bad effects previously noted.

It is my object to draw wire without slip on any drum, and thus to preserve intact the coating on the wire in its entire course through the machine. This object is accom-

plished by providing means whereby the stress in the wire passing to a given drum regulates the speed of that drum. Other objects contributing to the one above stated 5 appear from the following description of machines embodying certain practical forms of the invention.

The invention consists in the principles embodied in said machines and in the means 10 (and all substantial equivalents of such means) here illustrated and described in detail.

In the drawings,—

Figure 1 is a front elevation partly broken 15 away of one form of machine embodying the invention.

Figure 2 is a plan view partly broken away of the same machine.

Figure 3 is a vertical cross section taken 20 on a plane through the axis of the drums.

Figure 4 is a cross section on an enlarged scale taken on line 4-4 of Figure 3 illustrating a detail of mechanism.

Figure 5 is an elevation showing on an 25 enlarged scale one form of mechanism for controlling the speed of a drum by the tension of the wire passing to such drum.

Figure 6 is a plan view, further enlarged, 30 of a wedge member which forms a part of the mechanism shown in Figure 5.

Figure 7 is an elevation of said wedge member.

Figure 8 is a fragmentary view showing 35 in radial section a part of one of the friction power transmitting disks.

Figure 9 is a diagrammatic elevation illustrating the speed changing friction gearing of this mechanism.

Figure 10 is a plan view of the yoke forming 40 part of the means for shifting the transmission friction rolls.

Figure 11 is a plan view of the transmission roll holder combined with the transmission rolls and part of the means for shifting 45 the latter.

Figures 12 and 13 are, respectively, an elevation and a plan view of another form of machine embodying essentially the same invention, parts being broken away and shown 50 in section.

Figure 14 is an elevation of a modification of the mechanism shown in Figure 5 adapted to operate an electric control.

Like reference characters designate the 55 same parts wherever they occur in all the figures.

Referring first to Figures 1 to 4 inclusive, 15 represents the frame of a continuous wire drawing machine having three dies and 60 three drawing drums. The first and second dies 16 and 17, respectively, are mounted side by side in a holder 18 and the third die 19 is mounted on a holder 20. The first drum is shown at 21, the second at 22, and 65 the third at 23, the latter being the finishing

drum and constructed to hold an accumulation of wire. The course of the wire is from a reel or other suitable holder (not shown) through the die 16 and over and around the drum 21 in a sufficient number of wraps to 70 give the required tension, then under and around a guide roll 24 which is mounted on a bracket 25 at the adjacent end of the machine, then through die 17 and around the drum 22, then through the die 19 and to the 75 finishing drum 23. *w* represents the wire in Figures 1 and 2, and the arrows there applied indicate the course of its travel. A drum 26 beside the drum 22 is provided for use, according to usual practice, when first 80 threading the wire through the dies.

The drums 21, 22, and 26 are mounted on the same axis, all being supported by a shaft 27 which turns in suitable bearings in the side walls of the frame 15. Drum 26 is secured directly to this shaft, drum 22 is secured to a tubular shaft 28 which surrounds and is adapted to turn on the shaft 27, and drum 21 is secured to a tubular shaft 29 which surrounds and is adapted to turn on the tubular shaft 28. For convenience of description the tubular shafts 28 and 29 will generally be called "quills" in this specification.

The drive for the drums last particularly described comprises a shaft 30 having bearings at 31 and 32, which shaft is rotated by a belt pulley or any other suitable means, not shown. On this shaft is mounted a pinion 33 in mesh with a large gear 34, fixed to the shaft 27. Gear 34 is also a planet gear carrier and is provided with one or more studs 35 (three being shown in this drawing) on each of which is mounted a planet pinion 36. These planet pinions mesh simultaneously with a sun gear 37 fast on the inner quill 28 and with an internal annular gear 38 fast on the outer quill 29.

This planetary gearing permits the drums 21 and 22 to adjust themselves as to their respective speeds automatically to the tension and rate of delivery of the wire. Thus, for example, if the elongation of the wire in the second die should diminish, its lower rate of delivery to the drum 22 would hold back the drum, which would cause the drum 21 to be driven at a rate of speed relatively faster until a balance is reached in which the wire is drawn through the first die and delivered to the second die at the rate called for by the second drum. Thus slipping of the wire is eliminated as a necessity or possibility in this part of the machine.

For driving the third or finishing drum, the following mechanism is provided, which mechanism is additionally illustrated on enlarged scales in Figures 5 to 11. The main shaft 30 carries a bevel pinion 39 in mesh with a complementary pinion 40 on a transmission shaft 41, on which shaft there is also

secured a bevel pinion 42 in mesh with a complementary pinion 43 which is loosely mounted on an upright shaft 44, said shaft having bearings in a bracket 45 and in the 5 cover plate or top wall of the machine.

A collar 46 is made fast by a key or otherwise to the shaft 44 and is connected by a spring 47 with the gear 43, said spring being so arranged that it transmits the driving torque of the gear to the shaft in a yielding manner which permits the gear to run ahead of the shaft when the load on the latter increases, in proportion to the increase of load, and causes the shaft to follow with an 10 increase of speed when the load diminishes.

An annular cam or wedge 48 surrounds the hub of gear 43 and is secured thereto with provision for angular adjustment by a set screw 49. This annular wedge is shown in 20 detail in Figures 6 and 7 and as there shown is provided with two oppositely arranged and equally inclined wedge abutments 50 and 51.

A sleeve 52 is keyed or splined to the 25 shaft 44 so that it must rotate with the shaft but is capable of moving endwise thereon, and such sleeve surrounds the spring 47 and extends close to the wedge 48, having inclined surfaces 53 complementary to the 30 wedge abutments of the latter. By means of these inclined surfaces, when the gear 43 runs ahead of the shaft 44, sleeve 52 is raised along the shaft, and when the spring turns the shaft faster than the gear, said 35 sleeve descends under the weight of the superposed parts, or by the pressure of a suitably arranged spring which may be provided if necessary.

Sleeve 52 is coupled, by means of a swivel 40 coupling 54, with a yoke 55 mounted slidably on the shaft 44 but prevented from rotating with the shaft by means of an anchor link 56 (Figure 10) which is hinged at one end to the yoke and at the other end 45 to a bracket 57 fixed to a convenient adjacent part of the machine frame. Any sort of swivel coupling may be provided at 54 which is adapted to transmit endwise movement from the sleeve to the yoke but permits the sleeve to rotate without turning 50 the yoke. The coupling here shown is internally threaded at its upper end and screwed upon a sleeve 58 which rotates on a bushing 59 secured in the hub of the yoke 55 and is retained by a lip or shoulder 60 on the end of said bushing.

A friction driving disk 61 is keyed on 60 shaft 44 and a similar complementary opposed friction disk 62 is mounted in a slideable manner on the hub of a pinion 63 which is adapted to turn about the shaft, and between which and the upper bearing of the shaft is interposed a ball thrust bearing 64. Adjusting and lock nuts 65, 66 threaded 65 on the hub of pinion 63 enable the disk 62 to

be set at the proper distance from disk 61 to be driven frictionally from the latter by means of the interposed friction rolls 67.

The latter rolls are preferably four in number equally distributed about the axis 70 of the shaft, but there may be more or fewer, if desired. Each of these rolls is mounted rotatably between the jaws of a holder 68 which is adapted to turn about a horizontal axis at right angles to the axis 75 of the roll in a bearing 69 on a carrier 70. Said carrier surrounds the shaft 44 and is made fast to the frame by an arm 71, or other convenient means, so that it cannot 80 rotate. Each roll holder is provided with an arm 72 connected by a link 73 with an adjacent part of the yoke 55. The arms 72 of the respective transmission rolls and the links 73 connected thereto are so proportioned and arranged that endwise movement of the yoke 55 on the shaft gives equal oscillative movement of the same character simultaneously to all of the transmission rolls. These rolls are arranged with their 85 axes radial to the disks 61 and 62 and their rims in contact with runways 74 in the adjacent faces of the disks. Said runways are concentric with the shaft 44 and are concave radially to the shaft with a radius of curvature equal to the radius of the transmission rolls. Hence the oscillative movement given to the transmission rolls causes 90 their points of contact with the two disks to be shifted oppositely, whereby the radius of the line or path of contact on one disk 95 is lengthened and on the other disk is shortened.

These displacements are diagrammatically shown in Figure 9. When the mid plane of the roll occupies the position designated by the line *a*—*a* of that figure, being parallel to the shaft 44, disk 62 is driven at the same speed as 61; but when this plane is shifted to the position *b*—*b*, disk 62 is 100 driven slower; and when shifted to the position *c*—*c* disk 62 is driven faster than 61. Rise of the sleeve 52, transmitted through the connections just described, turns the transmission rolls in the direction from position *c*—*c* to position *b*—*b*, while descent 110 of the said parts has the opposite effect.

Pinion 63 drives the finishing drum 23 through an idler gear 75 and a gear 76 fixed to the shaft of said drum.

In operation the wedge 48 is so adjusted 120 that when the wire passing to the drum 23 is under normal tension, the transmission rolls 67 will be in the mid position. Then, so long as the tension remains of the predetermined degree the finishing drum rotates at constant speed. If, however, the tension in the wire should become greater, the additional load imposed on the shaft thereby causes the shaft to lag and the wedge cam to be turned relatively to the 130

cam follower 52, which causes the follower and the yoke, or roll controller, to be raised and the rolls to be turned to a position where the disk 62 is driven at a reduced speed. Eventually a speed is reached at which the take up of the drum equals the delivery of the wire and a sufficient tension to avoid slipping on the preceding drums is maintained in the wire.

10 Figure 14 shows the same principle applied to an electric drive. Here the shaft 41, gears 42, 43, wedge cam 48 and follower 52 are substantially the same as already described, but the follower, instead of controlling a friction transmission, controls the contact arm or coupler 77 of a rheostat over the contact buttons 78. The short arm of a lever of which 77 is the long arm occupies a groove 79 in the cam follower and is raised or lowered by the movement of the latter. The rheostat controls the amount of current delivered to an electric motor which is mechanically connected to drive the finishing drum.

15 Figures 12 and 13 show a machine which is like in principle to that first described, but different in detail in its accommodation to a tandem arrangement of dies and drums. Here the first, second and third dies are

20 designated 81, 82 and 83, respectively, and the corresponding drums 84, 85 and 86, respectively, all arranged in tandem on separate parallel shafts 87, 88 and 89 driven by bevel gearing from a main shaft 90. The drive for the first drum is direct through the gears 91 and 92, but for the following drums is effected through gears 93 and 94 and a friction transmission consisting of a disk 95, like the disk 61, fast to the gear 94, and a disk 96, like the disk 62, fast to the shaft 88, in the one case, and 89 in the other. A transmission roll 97, interposed between the friction disks, is mounted in a holder 98 adapted to rock in a bearing 99 secured to the frame.

25 The wire in passing from each preceding drum to the next in the series extends around guide rolls 100 and 101, the latter delivering the wire in the line of the next die, and the former being carried on a rock arm 102 which is pivoted at its lower end to a bracket 103 on the base of the frame. A coupling link 104 extends from the upper part of the rock arm 102 to an arm 105 on the transmission roll holder.

30 Increased tension of the wire causes displacement of the roll 100 in that direction which causes rocking of the transmission roll in the manner to reduce the speed of the driven drum. A suitably arranged

35 spring 107 applied to the arm 102 opposes such displacement of the guide roll and restores it when the tension of the wire relaxes.

40 In this specification the descriptive terms used have been chosen for their aptness to the particular embodiments of the invention

illustrated, but not with intent to limit the protection which I claim to the specific forms thus designated. It is to be understood, then, that all such terms are to be construed, for the purpose of determining the range of equivalents included within the scope of the claims, according to the purpose, function and effect of the parts which they designate rather than with reference to the particular form or construction of such parts. With special reference to the planetary gearing shown in Figures 1 to 4, it may be observed that such gearing is a differential mechanism and it may have other specific forms than that shown in said figures. The internal gear 38, although it surrounds the planet gears, is essentially a sun gear equivalent in function and effect to the sun gear 37, and may be so called for the purpose of generic definition.

45 What I claim and desire to secure by Letters Patent is:

1. In a continuous wire drawing machine, a source of power, two dies arranged in series, two drums each of which is arranged to draw wire through one of said dies, differential gearing connected with said two drums and the source of power, respectively, a third die, a third drum to draw the wire through said third die, a yielding connection between the source of power and said third drum, and means operated in consequence of the relative movement of said yielding connection for regulating the speed of said third drum, whereby to prevent slip of the wire on the first two drums.

50 2. In a continuous wire drawing machine, a source of power, two dies arranged in series, two drums mounted to draw wire, each through one of said dies, differential gearing connected to said drums and the source of power for driving the drums, a third die to which wire is delivered from the second in series of the first two drums, a third drum around which the wire passing from said third die is wrapped, said third drum being yieldingly connected to the source of power, and means arranged and operative to cause the stress on the wire drawn through the third die to adapt the speed of the third drum to the tension and rate of delivery of the wire thereto.

55 3. In a wire drawing machine, a source of power, a die, a drum around which wire passing through said die is wrapped, a yielding transmission means between the source of power and the drum, adapted to permit lagging of the drum with increase in the tension of the wire, means controlled by such lagging for altering the speed of the drum, and provisions for adjusting the tension of said yielding transmission means.

60 4. In a wire drawing machine, the combination with a drawing drum, a die through which wire passes to said drum, and

a source of power, of speed regulating mechanism for the drum comprising a cam element driven by the source of power, a shaft coupled to the drum and movable about its axis independently of said cam element, a spring interposed between the cam element and shaft for transmitting motion yieldingly from the former to the latter, a cam follower rotatable with said shaft, 5 but otherwise displaceable thereon arranged to be displaced by and in consequence of relative movement between the shaft and cam element, and speed varying mechanism for the drum connected for operation by displacement of said follower.

5. In a wire drawing machine, the combination with a drawing drum, a die through which wire passes to said drum, and a source of power, of speed regulating mechanism 20 for the drum comprising a cam element driven by the source of power, a shaft coupled to the drum and movable about its axis independently of said cam element, a spring interposed between the cam element and shaft for transmitting motion yieldingly from the former to the latter, a cam follower rotatable with said shaft but otherwise displaceable thereon arranged to be displaced by and in consequence of relative 25 movement between the shaft and cam element, and speed varying mechanism for the drum connected for operation by displacement of said follower, said cam element being adjustable to vary the tension of said 30 spring.

6. A wire drawing machine comprising a series of dies and drawing drums alternating with one another through and around which, respectively, the wire is passed, differential planetary driving mechanism for 40 the first two drums of the series consisting of a sun gear coupled with one of said drums, a second sun gear coupled with the other of said drums, and a planet pinion in mesh with both the aforesaid gears and power driven in its orbit, driving means for the third drum of the series including spaced apart disks and a transmission roll between and in frictional contact at its rim with 45 said disks, and means controlled by the tension of the wire passing to the third drum for so inclining said roll as to shift its point of contact with one of the disks nearer to the axis of that disk and its point of contact with the other disk farther from the axis of the last named disk, whereby to 55 vary the speed of said third drum in proportion to a change in the rate of delivery of the wire thereto.

7. In a continuous wire drawing machine, a plurality of drawing drums around which the wire is wrapped in series, a die in advance of each drum, a differential planetary mechanism coupled with the first two drums 60 of the series, whereby the speeds of said

drums are automatically regulated in proportion to the tension and rate of delivery of the wire passing to said drums, respectively, a power driven mechanism for a following drum of the series including a spring 70 transmission member adapted to yield with increase in the tension of the wire passing to said drum and to advance the drum upon lessening of said tension, and means governed by the relative motion of the spring connected parts of said driving mechanism 75 for controlling the rate of speed of said drum.

8. In a continuous wire drawing machine having more than two drums and as many 80 dies, arranged one in advance of each drum, power means including a differential mechanism applied to drive two of said drums, yielding power transmission mechanism driving the third drum, and means operated 85 by the yielding of said mechanism for governing the speed of said third drum.

9. In a wire drawing machine, a drawing drum, a driving shaft, two disks coaxially mounted on said shaft, one of which is fixed 90 to the shaft and the other is loose thereon and is geared to the drum, a friction transmission roll mounted between said disks and in contact at its periphery with the opposed 95 faces of the disks, a holder for said transmission roll arranged to permit inclination of the plane of said roll to different angles with the axis of the shaft, a power actuated driver for the shaft, a spring interposed between said driver and the shaft for transmitting force to the latter, and connections 100 operated by relative motion between said driver and the shaft for altering the angle between the plane of said roll and the shaft.

10. In a wire drawing machine, a drawing drum, a driving shaft, two disks coaxially mounted on said shaft, one of which is fixed 110 to the shaft and the other is loose thereon and is geared to the drum, a friction transmission roll mounted between said disks and in contact at its periphery with the opposed faces of the disks, a holder for said transmission roll arranged to permit inclination of the plane of said roll to different angles 115 with the axis of the shaft, a power actuated driver for the shaft, a spring interposed between said driver and the shaft for transmitting force to the latter, and connections operated by relative motion between said 120 driver and the shaft for altering the angle between the plane of said roll and the shaft, said disks having runways in their opposed surfaces curved radially of the respective disks with a radius of curvature equal to the 125 radius of the transmission roll.

11. In a wire drawing machine, a wire drawing drum, driving means for said drum including a shaft, a power impelled driver coaxial with said shaft but movable inde-

- pendently thereof, a spring connecting said driver and shaft with provision for yieldingly resisting movement of the former relatively to the latter, a cam or wedge member connected with the driver, a follower complementary to said cam arranged to be displaced by the latter in consequence of relative movement between the driver and shaft, and means by which the displacement of said follower causes variation in the speed of rotation imparted to the drum.
12. A wire drawing machine comprising drums arranged in series adapted to receive windings of wire and to draw the wire, a die arranged for wire leaving one drum to pass through it in course to a subsequent drum of the series, driving means for said subsequent drum, a transmission spring between said driving means and said subsequent drum adapted to permit lagging of the driven part with increased tension of the wire, and speed governing means operated by lagging of such driven part for reducing the speed imparted to the driven part.
13. In a continuous wire drawing machine having a plurality of dies, and a plurality of drums, arranged in series, means for driving a subsequent drum of the series including disks independently rotatable on the same axis and spaced apart, a transmission roll between and in frictional contact with the disks, and means controlled by the tension of the wire in passing to said subsequent drum operative to incline the roll in such manner that its point of engagement with one of the disks is shifted toward the axis and its point of engagement with the other of the disks is shifted away from the axis.
14. In a continuous wire drawing machine, a plurality of drawing drums around which the wire is wrapped in series, a die arranged for the wire to pass through it in its course to each drum, a variable speed friction drive for a subsequent drum of the series, said drive comprising friction disks in parallel planes, one of which is connected with said subsequent drum and the other is driven from a source of power, and an intermediate transmission roll between and in contact with both said disks mounted on the same side of the axes of both disks with its own axis approximately radial thereto and with provision for adjustment to bring its point of contact with one disk nearer to the center of said disk and its point of contact with the other disk farther from the center thereof at the same time, and means by which a change in the tension of the wire passing to said subsequent drum from the preceding drum effects such an adjustment of the transmission roll.
15. In a continuous wire drawing machine, a drum about which the wire is wrapped and by which it is drawn, a die through which the wire is drawn in passing to said drum, approximately coaxial frictional driving disks arranged in parallel planes, one of which is coupled to the drum, and an intermediate frictionally acting transmission roll between and in contact with both said disks, said transmission roll having its axes in a radial plane of the disk axes and being shiftable about an axis perpendicular to such plane to increase the speed ratio of the mechanism, and means controlled by the tension of the wire passing to said die for shifting said transmission member.
16. In a wire drawing machine, a drawing drum, a driving shaft, two disks coaxially mounted on said shaft, one of which is fixed thereto and the other is loose thereon and is coupled to the drum, a friction transmission roll mounted between said disks and in contact at its periphery with the opposed faces of the disks, a holder for such transmission roll arranged to permit inclination of the plane of said roll to different angles with the planes of the disks, and means controlled by the tension of the wire passing to said drum and operative to move said holder so as to alter the inclination of the roll when a variation in such tension occurs.
- In testimony whereof I have affixed my signature.

JAMES A. HORTON.
